(57) **CLAIM**

The ornamental design for a car door restraining device, as shown.

DESCRIPTION

FIG. 1 is a top plan view of a car door restraining device showing a first embodiment of our new design.

1 Claim, 6 Drawing Sheets

FIG. 2 is a partial cut away top plan view of a portion of the car door restraining device circled in FIG. 1 showing the locking mechanism.

FIG. 3 is a side elevational view of the first embodiment of the car door restraining device.

FIG. 4 is a bottom plan view of the car door restraining device.

FIG. 5 is a top perspective view of the car door restraining device shown in FIG. 3.

FIG. 6 is a bottom perspective view of the car door restraining device shown in FIG. 3.

FIG. 7 is a top plan view of a car door restraining device showing a second embodiment of our new design.

FIG. 8 is a partial cut away top plan view of a portion of the car door restraining device circled in FIG. 7 showing the locking mechanism.

FIG. 9 is a side elevational view of the second embodiment of the car door restraining device.

FIG. 10 is a bottom plan view of the car door restraining device, shown in FIG. 9.

FIG. 11 is a top perspective view of the car door restraining device shown in FIG. 9; and,

FIG. 12 is a bottom perspective view of the car door restraining device shown in FIG. 9.

FIG. 8

FIG. 12
